UNITED STATES PATENT OFFICE.

ALLAN C. HARRINGTON, OF CHICAGO, ILLINOIS.

ELECTRIC STOVE.

1,388,111.

Specification of Letters Patent. Patented Aug. 16, 1921.

Application filed May 28, 1920. Serial No. 384,834.

To all whom it may concern:

Be it known that I, ALLAN C. HARRINGTON, a citizen of the United States, and a resident of Chicago, Illinois, temporarily residing in 5 Cedar Rapids, Iowa, have invented a new and Improved Electric Stove, of which the following is a full, clear, and exact description.

This invention relates to electric stoves, 10 and has particular reference to one in which thermostatic control of the generated heat is provided.

An object of the invention is to provide a simple, compact electric stove in which the 15 generated heat is under a much finer degree of control than is usually the case.

Another object is to provide a thermostatic device in which the response of the thermostatic element to the generated heat 20 is uniform and sensitive to a very high degree.

Still another object is to provide a means whereby the heater circuit may be opened and closed at predetermined temperatures 25 by the use of a simple and readily operable adjusting means in connection with the thermostat.

The invention in general comprises a receptacle having double walls between which 30 there is a vacuum and which contains an electrical heating element. Also located within the receptacle is a thermostatic device in the form of a coiled spring of heat-responsive material. This spring is connected to suitable linkage, whereby a lever arm connected thereto on the exterior of the receptacle is moved either to indicate the temperature within the receptacle or to move 35 a switch or to perform some other function.

40 In order to insure that the expansion and contraction of this coil spring may be very uniform and result in an increased sensitivity of the device, it is provided that at frequent intervals throughout its length the 45 coiled spring is confined on both sides by guiding elements, so that when a tendency exists to expand under heat, the general configuration of the spring when coiled is maintained and the expansion takes place substantially entirely along the length of the 50 spring. In this way an increased movement of the spring is obtained which is effective to move the indicator or other device on the exterior of the receptacle.

55 This thermostatic element is connected by

suitable means to a rotatable element on the exterior of the receptacle. Adjacent this rotatable element is an electric circuit closer. The circuit closer is connected to the rotatable element by means of an adjustable link, 60 the position of which may be varied at will, to determine the amount of movement of the rotatable element required before its movement results in either the opening or closing of the circuit closer.

65 The invention is illustrated in the drawing, of which—

Figure 1 is a longitudinal section of the stove taken on the line 1—1 of Fig. 2;

Fig. 2 is a plan view of the stove;

Fig. 3 is an enlarged plan view of the top of the circuit-controlling means located on the top of the stove;

Fig. 4 is a vertical section taken on the line 4—4 of Fig. 3;

Fig. 5 is a horizontal section taken on the line 5—5 of Fig. 4; and

Fig. 6 is a detail view of the circuit-closer terminals.

As illustrated in the drawings, the invention comprises a receptacle having inner and outer walls 1 and 2 and a tight-fitting cover, which also has inner and outer walls 3 and 4. These walls may be made of any suitable material, such as glass, porcelain or metal, 85 and may be joined in an air-tight manner by any method known in the arts. Between the inner and outer walls of the receptacle and the cover, a vacuum may be provided, by any suitable method, or insulating packing of any well-known character may be placed therein to more effectively prevent the radiation and conduction of heat from the interior of the receptacle to the exterior.

90 Positioned within the receptacle, preferably on the bottom, is a heater element, represented by the numeral 5. This element 5 is only diagrammatically represented, since it may be of any well-known and suitable form. A pipe 6 extends from this element 95 5 to the exterior of the receptacle and passes through the space between the walls to the outside and provides a passage for the circuit wires 7 and 8. These wires extend to a circuit closer to be hereinafter mentioned.

100 The cover of the receptacle is connected thereto in any suitable manner and is provided on its inner surface with a casing 9, which may be riveted or screwed thereto. This casing 9 contains a coiled spring 10,

105

110

which is of any suitable metal which is particularly responsive to changes in temperature. This spring is wound in a flat spiral, the inner end of the spring being connected 5 to a shaft 11 and the outer end being connected by a pin to a plate 12. The plate 12 is loosely mounted on the shaft 11. This shaft 11 is, at its lower end, fixed in the casing 9 and extends upwardly from the casing 9 in a tube 13, which tube is sealed between the inner and outer walls of the cover so as to make it air tight. The upper end of the shaft 11 is fastened to a plate 14 on the top of the cover. Along part of its 10 periphery the plate 12 is provided with teeth 15 which are adapted to mesh with a pinion 16 mounted on the lower end of shaft 17 and which extends upward from the casing 9 in a tube 18, similar to the tube 13, and at its upper end is connected to a plate 19. The plate 19 is provided with a slot in the form of a sector 20. A link 21 is loosely pivoted to the upper end of shaft 17 and, 15 intermediate its length, is provided with an adjustable nut 22, a portion of which rides in the slot 20. This nut and slot arrangement provides means whereby the link 21 may be adjusted in any position with respect to the plate 19. The outer end of the 20 link 21 is connected by a spring 22 with arm 23 of a circuit closer. This arm carries a contact plate 24 on its outer end, which is adapted to dispose itself between terminal springs 25 and 26 which are adapted to be 25 connected to the circuit wires 7 and 8.

It will be readily seen that by varying the position of the link 21 in the slot 20 more or less movement will be required of the plate 19 under the influence of the thermostatic element in order to either open or 30 close the switch, as the case may be, so that a rather wide degree of adjustability is provided by this simple means.

As more clearly shown in Figs. 4 and 5, 35 a plurality of pins 27 are securely fastened to one face of the casing 9. These are spaced apart at short intervals in lines which preferably, and as shown, extend at right angles to each other. The spring 10 is threaded in a flat spiral form between these pins, which, therefore, confine the lateral movement of the spring at frequent intervals throughout its length. The spring, therefore, in expanding is prevented from 40 moving laterally to any substantial degree and, therefore, tends to move entirely in a longitudinal direction, thereby resulting in the most efficient indication for any given change of temperature.

By the mechanism and the arrangement 45 thereof above described it will be readily seen that I have provided a simple, compact stove, adapted to be heated electrically, in which a simple and easily adjustable 50 heat-controlled device is located and in

which the movements of elements connected with the thermostatic device are more uniform and sensitive due to the applications of the various features of my invention.

It is clear that changes in form and arrangement of certain of the parts may readily be made without departing from the spirit of the invention as set forth and hereinafter claimed.

What I claim is:

1. An electric stove comprising a receptacle, a heater element within said receptacle, a thermostatic device within said receptacle, a circuit closing arm, an element coöperating with said thermostatic device 75 and movable in response to the movement thereof, said element coöperating with said circuit closing arm, connections between said element and said circuit closing arm, and means for adjusting the relation of said connection with respect to the circuit closing arm and said element.

2. An electric stove comprising a receptacle, a heating element within the receptacle, a thermostatic device within the receptacle, a circuit closing arm, a rotatable member operatively connected to said thermostatic device and coöperating with said circuit closing arm, an arm on said rotatable member, said arm connected to said 90 circuit closing arm, and means for adjusting the relation of said arm with respect to the circuit closing arm and the rotatable member.

3. An electric stove comprising a receptacle, a heater element within said receptacle, a thermostatic device within said receptacle, a rotatable plate operatively connected to said thermostatic device and having a circular slot therein, a circuit closer, 100 an arm connected to said rotatable plate and to said circuit closer, and means connected to said arm and operatively associated with the slot to adjust the arm with respect to the rotatable plate and determine the character 105 of the opening and closing of the circuit closer.

4. A thermostatic device comprising a coiled spring one end of which is free to expand, means positioned at intervals 115 throughout the length of the spring to confine its movement substantially to a direction coincident with its length.

5. A thermostatic device comprising a coiled spring one end of which is free to 120 expand, a plurality of devices positioned along the length of the spring to confine the spring to its original configuration when cold so that when expanding under the influence of heat this original configuration is 125 maintained and the expansion is substantially entirely longitudinal.

6. A thermostatic device comprising a coiled spring one end of which is free to expand, stationary devices positioned at in- 130

tervals throughout the length of the spring to prevent lateral movement of the spring in expanding.

7. A thermostatic device comprising a coiled spring one end of which is free to expand, a plurality of pins positioned on both sides of said spring at intervals throughout its length, said pins adapted to confine the movement of the spring to a direction parallel with itself.

8. A thermostatic device comprising a

coiled spring one end of which is free to expand, a plurality of devices positioned along the length of said spring to confine it to a longitudinal movement, a movable plate fastened to the free end of the frame, a shaft operatively connected on the said movable plate, an arm on the outer end of said shaft, and an indicating device connected to and operated by said arm. 15

ALLAN C. HARRINGTON.
